UNITED STATES PATENT OFFICE.

FRANK SUTTIN, OF LOS ANGELES, CALIFORNIA, ASSIGNOR OF ONE-HALF TO G. G. VOEGE, OF LOS ANGELES, CALIFORNIA.

CLASP FOR BRACELETS AND WRIST WATCHES.

Application filed June 29, 1925. Serial No. 40,379.

This invention relates to a clasp which is especially useful when applied in the construction of wrist watches and particularly to a type of wrist watch in which the watch 5 may be detached from the bracelet and the bracelet transformed into a regular bracelet without a wrist watch.

It is very desirable that the bracelet holding the wrist watch should fit tightly on the wrist so as to prevent the watch from moving about. The clasps usually carried by bracelets are constructed in such a way as to necessitate the introduction of the finger under the clasp in closing or opening it. This necessitates the bracelet being somewhat loose to permit the introduction of the finger.

The general object of my invention is to produce a clasp of simple construction which can be readily opened and closed without necessitating the introduction of the finger between it and the wrist; also to provide a clasp which is particularly adapted for connecting a wrist watch into a bracelet.

Further objects of the invention will appear hereinafter.

The invention consists in the novel parts and combination of parts to be described hereinafter, all of which contribute to produce an efficient clasp for a bracelet and wrist watch.

A preferred embodiment of the invention is described in the following specification, while the broad scope of the invention is pointed out in the appended claims.

In the drawings:

Fig. 1 is a plan of the bracelet when worn as a wrist watch, the view being upon a somewhat enlarged scale.

Fig. 2 is a side elevation of the wrist watch with its connected side members, and showing short portions of the adjacent ends of the wrist band of the bracelet.

Fig. 3 is a plan showing the ends of the wrist band which lie adjacent to the watch, and illustrating the construction and the way in which my clasp facilitates the transforming of a wrist watch bracelet into an ordinary bracelet.

Fig. 4 is a side elevation showing the parts illustrated in Fig. 3, but showing them in different positions so as to further illustrate details of their construction.

Fig. 5 is a side elevation of the type of clasp which I prefer to employ as the side

members which connect the wrist watch to the ends of the wrist band.

Fig. 6 is a perspective of a type of clasp very similar to that shown in Fig. 5 and illustrating the same in its open position.

Fig. 7 is a perspective of a clasp of the same type as shown in Fig. 5 but with a narrow hook adapting it to be employed with the type of watch which is convertible from an ordinary watch to a wrist watch and in which two small rings are provided at diametrically opposite points on the watch; one of these rings is the usual ring mounted at the watch stem.

Fig. 8 is a side elevation of a clasp showing another embodiment of the invention in which the resiliency, which enables the closure or cover of the clasp to snap shut, is supplied by a separate spring; and in this type a special feature is embodied for increasing the security with which the hook is attached to the ring or staple of the wrist watch.

Fig. 9 is a section taken about on the line 9—9 of Fig. 8.

Fig. 10 is a vertical cross section taken about on the line 10—10 of Fig. 8.

(It is to be understood that in Figs. 5 to 10 the clasps are shown upon a highly magnified scale.)

Referring to Fig. 1, the wrist watch 1 is mounted in a wrist band 2 being connected to the ends 3 of the wrist band by side members 4. These side members are wide at their inner ends so as to attach to elongated eyes 5 formed at the sides of the watch case, and are elongated and of narrower width throughout their length.

In the drawing, both of these side members 4 are constructed as clasps. In practice, it is only necessary that one of them should be in the form of a clasp; however, it is essential that one of the side members shall be in the form of a clasp in order to enable it to be disengaged from the wrist watch preparatory to disconnecting it from the wrist band. When the disconnection is made at one side, of course the watch with the side member on the other side may be also disengaged from the adjacent end of the wrist band.

In order to accomplish the removal of the wrist watch with the side members, I prefer to construct the end of each side member with a threaded stud 6, and the end link 7

of the wrist band which lies adjacent to this side member is provided with a threaded socket 8. I prefer to employ this form of fastening because it is very secure and at the same time it is not difficult to operate in attaching the parts together. However, any suitable fastening means may be employed for securing the outer end of the side member to the adjacent link of the chain or wrist band. The links 9 of the wrist band are preferably connected together by hinge joints 10 on their inner sides, that is to say, on the side which lies toward the wrist.

Although I prefer to construct one of the side members 4 as a clasp of special construction, any suitable detachable clasp may be employed which can be opened so as to disengage it from the eye 5 at the side of the watch. When the clasp or side member 4 is disengaged, it can of course be rotated so as to disengage its stud 6 from the wrist band. In this way, the watch and the side members can be completely removed from the band.

In order to transform the remaining portion of the wrist band into a complete bracelet, I provide a band-section 11 (see Figs. 3 and 4). This band-section includes a detachable clasp 12 which cooperates with an adjacent link 13 to enable all of the links of the band-section 11 to be connected together. As illustrated in Figs. 3 and 4, the clasp simply connects the end link of the band-section.

By reason of the clasp 12, it will be evident that the band section can be separated into two parts, as illustrated in Fig. 3. At each end of the band-section a threaded stud 14 is provided similar to the threaded stud 6 carried by the side members 4. These threaded studs 14 fit the threads of the sockets 8 in the end links of the wrist band. Therefore, in order to complete the bracelet, it is merely necessary to screw up the two ends of the band-section on the adjacent ends of the wrist band and then snap the clasp 12 into place, that is to say, it is merely necessary to close the bracelet and hold it closed by means of the clasp 12.

In order to give uniformity to the links of the complete bracelet, I prefer to attach the studs 14 to a hinged plate 15 on the ends of the links which carry them, each plate 15 being attached by a hinge connection 16.

Most of the clasps which are now employed in wrist watches or bracelets are impractical for the reason that it is usually necessary to insert one's finger between the clasp and the wrist in order to operate the clasp. I prefer to construct the clasps or side members 4 in such a way that this is not necessary, but so that they can be very readily opened or closed. For this purpose, I prefer to construct them of the type illustrated in Figs. 5 to 10.

These clasps are characterized by the fact that the body of the clasp is of shallow box form with a relatively large bottom wall to lie against the wrist, and this bottom has side flanges which extend along the body and which give stiffness to the body, and at one end the body is provided with a hook to engage the watch. Adjacent to this hook the flanges are provided with socket means which receives stud means which may be a transverse bolster carried on the cover or closure of the clasp, said cover or closure being in the form of an elongated plate conforming to the general outline of the body. The type of clasp illustrated in Fig. 6, has its body 17 provided with a hook 18 at one end, the side flanges 19 of the body being provided with socket means or throats 20. These throats are preferably connected by a tube 21 which extends transversely of the body and connects the side flanges, such tube being open on its upper side. While it is not absolutely necessary to use this tube, I prefer to do so in this type of clasp because it greatly increases the areas of contact which are rubbed together when the clasp is closed or opened. The closure of the clasp is in the form of a plate or cover 22 which is hinged at 23 at the end of the body remote from the hook 18, and this cover is provided on its under side with a transverse bolster 24 which is in the form of a round bar brazed or otherwise secured to the under face of the cover. This bolster and the socket means are so constructed that the bolster will move bodily laterally and snap into the socket when the plate or cover 22 is pressed down.

When the plate 22 is closed, its end projects over the opening or throat 25 which leads into the hook 18—in other words, the closure 22 cooperates with the hook 18 to close the hook when the cover is closed.

In order to facilitate opening the cover plate 22 at will, I prefer to provide its upper side with an undercut button 26.

If desired, I may construct the hook of greater width than the body of the clasp (see Fig. 6, in which 27 indicates the hook). This hook as illustrated is of much greater width than the body of the clasp. In other respects the clasp may be constructed as illustrated in Fig. 5, that is to say, it presents a transverse socket 29 into which the bolster 30 snaps when the cover plate 31 is closed. Beyond the bolster 30 the cover plate 31 has an extension 32 which will project over the hook and prevent it from becoming disengaged from the eye of the wrist watch.

In some cases it may be desired to adapt the bracelet for use with convertible watches, that is to say, a watch in which the usual ring at the stem of the watch is supplemented by a smaller ring at a diametrically op-

posite point. In order to adapt the clasp to cooperate with a watch of that type, I may construct the clasp as illustrated in Fig. 7, in which I provide narrow hook 33 to take 5 hold of the watch ring. In other respects, the clasp may be constructed as already described, except that I terminate the cover plate 34 short of the hook, and I simply provide an elongated button 35 on the upper 10 side of the cover plate which projects over the hook and closes the opening into it.

If desired, the clasp may be constructed so that a separate spring is provided to give resiliency to the bolster which snaps into the 15 socket. In that case, I prefer to construct the clasp as illustrated in Figs. 8 to 10. In this type of clasp, the clasp has the usual shallow box-like body 36 with side flanges 37 having socket means 38 and on the under 20 side of the cover 39 a spring 40 is provided having two forks, each fork carrying a small roll or bolster 41. These rolls or bolsters 41 project at their ends beyond the sides of the body. With this construction, it will be 25 evident that by pressing in on the ends of the bolsters or rolls 41, they may be disengaged from the socket means or sockets 38 to enable the cover to open.

With this type of spring catch, I prefer 30 to provide the end of the cover with a curved guard 42 which extends downwardly (see Fig. 8) and which would prevent the metal at the eye 5 of the wrist watch from coming in contact with the bolsters 41. This guard 35 42 is concave on the side toward the hook 43.

Although I have illustrated both the side members 4 as clasps, it should be distinctly understood that one of them may be permanently attached to the wrist watch. It is 40 only necessary that one of them should open in order to enable the wrist watch to be taken out and the band-section substituted for it in the bracelet.

It is understood that the embodiment of 45 the invention described herein is only one of the many embodiments this invention may take, and I do not wish to be limited in the practice of the invention, nor in the claims, to the particular embodiment set forth.

50 What I claim is:—

1. In a combination bracelet and wrist-watch, a clasp for attaching the wrist band

to the watch having a body with a relatively large flat wall to lie against one's wrist, and having a hook at one end to hook into the 55 side of the watch, a cover for the body pivotally attached to the body at the end thereof remote from the hook operating to swing toward or from said wall, said body having a transverse socket adjacent the hook, and a transverse bolster carried by the cover on its 60 under side constructed to snap yieldingly into the said socket when the cover is closed, said cover cooperating with the hook to close the throat of the hook. 65

2. A clasp for a wrist-watch having a shallow box-form body with a relatively large flat bottom wall to lie against one's wrist, and having a hook at one end, a snap cover having a hinge connection with the 70 other end of the body with its axis parallel with the bottom wall of the body, and having a transverse bolster on its under side, said body having a transverse socket open on its upper side and constructed to enable the 75 bolster to move bodily laterally in snapping into the socket, said cover cooperating with the hook when in its closed position to close the throat of the hook.

3. A clasp for a wrist-watch having a body 80 with side flanges, said flanges having socket means associated therewith, a snap cover pivotally attached to the side flanges at the end of the body remote from the socket means, and a catch on the under side of the 85 cover for engaging in the socket means when the cover is closed, said body having a hook to engage the watch and cooperating with the cover to close the throat of the hook when the cover is closed. 90

4. A clasp for a wrist watch or bracelet having a shallow box-form body with a relatively large bottom wall to lie against one's wrist, and having a hook at one end of said body, a snap cover hinged to the other end 95 of the body having means cooperating with the hook to close the same when the snap cover is swung toward the said bottom, said cover and said body having stud means and means cooperating therewith to hold the 100 cover in its closed position.

Signed at Los Angeles, California, this 27th day of May, 1925.

FRANK SUTTIN.
